(57) **CLAIM**

The ornamental design for a sample vial gripper, as shown and described.

DESCRIPTION

FIG. 1 is a top perspective view of a sample vial gripper showing my design;

FIG. 2 is a top view thereof;

FIG. 3 is a bottom view thereof;

FIG. 4 is a side view thereof;

FIG. 5 is an opposing side view thereof;

FIG. 6 is front view thereof;

FIG. 7 is a back view thereof; and,

FIG. 8 is a top view thereof in a state of use.

The broken lines shown in FIGS. 1-5 depict portions of the sample vial gripper that form no part of the claimed design. The additional broken lines shown in FIG. 8 depict environmental subject matter and form no part of the claimed design.

1 Claim, 6 Drawing Sheets
